UNITED STATES PATENT OFFICE

JOSEPH A. MARTOCELLO, OF PHILADELPHIA, PENNSYLVANIA

RAW-WATER ICE SYSTEM

Application filed January 1, 1923. Serial No. 610,081.

My invention relates to the air system of an ice plant and more particularly to the system of connections between the air laterals and the air tubes that dip into ice cans, and to the location of these tubes.

The purpose of my invention is to provide an improved system of connections from air laterals into ice cans that is easy and inexpensive to manufacture and adapted to 10 convenient and efficient use.

A further purpose is to provide tap connection into the usual commercial pipe lateral or header that will not work loose and leak in service.

15 A further purpose is to avoid dirt and scale from the lateral, which frequently clogs throttling orifices or contaminates the ice, by tapping at right angles to the flow and from the middle of the lateral.

20 A further purpose is to place the throttling orifice where it is accessible for cleaning and inspection, at the plug member of a plug and socket coupling between the air tube in the can and a flexible connection to the air 25 header or air lateral.

A further purpose is to provide a bank or group of connected air cans, handled as a unit, with automatic valve mechanism for turning on the air as the unit is connected up.

30 A further purpose is to fit the terminal of a flexible air pipe for connection with air pipes of different diameters.

A further purpose is to provide an offset terminal for connection with the air pipe to 35 keep the connections out of the line of movement of the ice during the discharge of the ice from the can.

Further purposes will appear in the specification and claims.

40 I have preferred to illustrate my invention by but one main form with minor modifications, selecting a form that is practical and effective, inexpensive and easy to manufacture and which well illustrates the principles involved.

Figure 1 is a fragmentary partly sectional elevation illustrating my invention.

Figure 2 is a top plan view of Figure 1 to reduced scale and showing the invention applied to several cans.

Figure 3 is a perspective view of a ring washer shown in Figure 1.

Figure 4 is a top plan view illustrating a somewhat different layout from that of Figure 2.

Figure 5 is a fragmentary vertical section through a tank and cans with a cover in place.

Figures 6 and 7 are sectional detail elevations showing in slightly modified forms the connection between the header and the air 40 tube for the layout of Figure 4.

Figure 8 is a top plan view illustrating a third form of layout.

Figure 9 is a fragmentary side elevation and vertical section through a can, air pipe 45 and connections.

Figure 10 is a side elevation of a terminal which may be used by me.

Figure 11 is a broken side elevation, partly in section, showing a terminal similar to 70 that of Figure 10 in position within an air tube.

Figure 12 is a fragmentary top plan view illustrating the connection to units or groups of cans within crates or baskets.

Figure 13 is a fragmentary side elevation of the structure seen in Figure 12.

Figure 14 is an enlargement of a portion 80 of Figure 12.

Figure 15 is an enlargement of a portion 80 of Figure 13.

Figure 16 is an enlarged section of Figures 11 and 12 showing the means for holding a lateral in a unit.

Figure 17 is a section through the automatic valve shown at the left in Figure 12.

Figure 18 is a section upon line 18—18 of Figure 17.

In all the figures like numerals refer to like 90 parts.

Describing in illustration and not in limitation and referring to the drawings:—

I take up first the invention as used in the layout of Figures 1, 2 and 3.

The air lateral 15 is tapped with T connection 16 and supplies diagonally opposite cans 17 with introduction of agitating air through flexible hose connections 18, plug and socket couplings 19 and air tubes 20, 100

loosely carried by brackets 21 from the sides of the ice cans 17.

To keep dirt and scale from entering the tap, I extend the tap shank 22 to approximately the middle of the lateral, where the air velocity is a maximum and the quantity of dirt and scale carried by the air is a minimum. Such dirt and scale as is present at the middle of the lateral is too heavy and its velocity is too high for it to turn at the abrupt angle requisite for entering the tap along with the relatively very light air. As a result the air enters the tap substantially free from dirt and scale.

15 I place a ring 23 of lead or other sufficiently plastic metal between the shoulder 24 of the tap fitting 16 and the lateral 15, to prevent the tap connection from working loose and leaking in service. I have used aluminum 20 also for this purpose.

The T is intended to be set in alignment with the lateral and the compressibility of the ring permits additional tightening of the T, if necessary to secure this alignment, 25 after the concave side 25 of the ring has been forced against the pipe by pressure of the T shoulder against the flat side of the ring.

The soft metal ring support around the shank of the T 16 gives the fitting adequate 30 support and tightness and permits a tightening of the T not only in alignment with the pipe but, if this be not desired, at any angular position with respect to the lateral.

The throttling orifice 27 between the lateral 35 and the air tube 20 is located upon the plug member 28 of the plug and socket coupling 19, giving very easy access to it for cleaning.

The projection of the end 19' about the orifice protects from clogging by any small 40 amount of dirt or scale and when there is enough accumulation in the pocket 29 formed to interfere with air passage the parts are readily disconnected and cleaned.

The socket member 30 of this coupling is 45 flared to guide the plug or a thawing needle and is drained at 31 to prevent ice from forming at this point.

In the layout of Figures 4 to 7, during the freezing operation the air tubes 20 hang from 50 a transverse lateral 15' which is temporarily placed across the tops of a number of cans, being fed in any suitable manner from a header or other supply not shown.

The air tubes are separately connected by 55 plug and socket coupling 19 to the flexible hose connections 32 carried by the tap fittings 16' which are tapped into the header.

As before the shank of the fitting is made 60 to extend substantially to the middle of the air-supply pipe, thus avoiding the entrance into the tube of dirt and scale with the air. As before the soft metal ring support 23 may be compressed between the air supply pipe and the shoulder of the tap, thus strengthening 65 the tap connection so that it may not

gradually work loose and leak in service. However, there is not as great advantage in the use of the ring as no special angular position is to be secured which would benefit (otherwise than in its effect in strength and avoidance of leakage) by an additional part of a turn.

70 As before, the throttling orifice is placed upon the plug member 28 of the coupling 19, and the flare of the socket member is provided 75 with a drain.

In all of these forms the T is given full opening from the lateral or header.

In Figure 7 I have shown the throttling orifice 23' placed at the entrance to the tap fitting to illustrate the advantage of the soft metal ring and inlet near the axis of the lateral even where the full advantage of my invention is not obtained by locating the throttling opening at the end of the flexible 80 connection farthest from the lateral or header. The drop tube could be directly connected to the flexible tube without terminal 85 28.

In the layout of Figures 8 and 9 the arrangement is substantially the same as in Figures 1 and 2 with the exception that the air tube is permanently fastened in one corner of the can instead of removably depending 90 along the can axis from a bracket.

95 If special measures have been taken to eliminate moisture from the air supply before it reaches the laterals, this arrangement is preferable in that the tube is more out of the way and does not have to be handled, but unless such special and relatively costly measures have been taken I prefer placing the tube near the can axis, where ice forms last and the tube is jacketed with water until the freezing operation is practically complete. As long as the tube is jacketed with water instead of ice the interior of the tube 100 remains free from accumulating ice and snow precipitated from the moisture in the incoming air, that rapidly collects if such special measures have not been taken to eliminate the moisture in the air before it reaches the tube.

105 In raw water ice systems where dehydrated air is used and where the air pipe within the can is against the side of the can, the desirability of having the water in the can initially as low in temperature as possible makes it freeze very rapidly after the can is submerged, giving but little time for connection 110 of the lateral to the air pipe. Sometimes before the terminal upon the flexible air connection is inserted within the air pipe the air pipe itself has frozen up preventing aeration of the can through that pipe. Under 115 these conditions it is very desirable to substitute another air pipe which may be put down within the unfrozen part of the can to save this can of ice from becoming opaque.

120 However, the terminal inlets for air pipes 125

intended to be separately supported in the can are usually larger than for those attached to the side of the can for the reason that the separately supported tubes must accommodate a thawing needle.

If the operator has delayed making the connection to the side of the pipe and has found it frozen up he can quickly and easily attach the same terminal to a drop tube, such 10 as may, for example, be carried by a bracket, by means of the terminal shown in Figure 10 in which I show two diameters of terminal 19' and 19², intended to fit the two sides of air pipes respectively. The smaller diameter of terminal 19' fits the side tube and the larger diameter 19² fits the separate tube.

Where a group or set of cans is rigidly held together within a basket, crate or frame 33, so as to make it possible to handle the 20 entire group or set as a unit, I provide for automatic opening of the air valve with connection of each set by an automatic valve of which a very desirable form is shown at 34. This automatic valve is held open in use for 25 flow of air from the header to the lateral, but when the lateral is disconnected from the header stops flow of air from the header protecting the header against air leakage. As shown the valve comprises male and fe- 30 male parts 35 and 36 of which the latter is secured at the left of Figure 12 in a header 37. A male or operating valve member is mounted upon a flexible pipe 38 secured to a lateral 39 which may be clamped by bracket 35 40 and hook bolt 41 against the side of the frame work or can.

The female valve member carries a valve seat 42 closed by a valve 43 mounted upon a stem 44, terminating in a cross bar 45. This 40 bar extends within an enlarged mouth 46 tapered to receive the tapered end 47 of the male member. The parts are proportioned so that the terminal 47 becomes air tight when the bar has been shoved by the end 48 45 of this terminal far enough to properly open the valve. The valve is automatically closed by the flow of air when the parts are disconnected.

A similar automatic valve member is se- 50 cured to the opposite end of the lateral so that each lateral carries a valve member at one end and an operating member at the other. As a result a series of sets or blocks can be connected, one to the other, each connection 55 automatically supplying air and each disconnection cutting off the air.

As the cakes of ice are discharged from the cans without disconnection of the lateral, I bend in two or more planes the terminal 19³ 60 by which the air taps 49 are connected through flexible pipes 18' with the corner air pipes 20. This enables me to keep the flexible pipes out of the path of ice discharge. The air pipes here are intended to be rigid with 65 the sides of the cans but by the use of two

different tube diameters for connection at 19³, if the pipe 20 becomes frozen up connection can be made with a separate pipe dropped into the can just outside of the frozen part in some such position as shown by the circle 50. 70

For convenience in making connections between the parts of the automatic valve I mount a handle upon the operating member of the valve at the end of its flexible connection, this handle being shown generically 75 at 51.

I appreciate that others skilled in the art, in view of my invention and disclosure, may see modifications and variations to meet individual whim or particular need and it is 80 my purpose to cover herein all such variations and modifications in so far as they fall within the reasonable spirit and scope of my invention.

Having thus described my invention what 85 I claim as new and desire to secure by Letters Patent is:—

1. In an air system for an ice plant, an air supply pipe, a tap therefrom extending into the pipe where the section of the pipe is curved, an annular shoulder on the tap outside of the pipe, a solid compressible ring around the tap on the pipe side curved to fit the contour of the pipe and bodily compressed between the shoulder and air pipe, 90 a can, an air-tube extending down into the can, and connections from the tap to the tube.

2. In an air system for an ice plant, an air supply pipe, a tap therefrom extending into the pipe approximately to the middle thereof where the section of the pipe is curved, an annular shoulder on the tap outside of the pipe, a solid compressible ring around the tap on the pipe side curved to fit the contour of the pipe and bodily compressed between the shoulder and the pipe, 105 a can, an air-tube extending down into the can, and connections from the tap to the tube including a reducing section.

3. In an air system for an ice plant, an air supply pipe, a tap therefrom extending into the pipe where the section of the pipe is curved, an annular shoulder on the tap outside of the pipe, a solid ring of compressible metal around the tap on the pipe side curved to fit the contour of the pipe and bodily compressed between the shoulder and the pipe, a can, an air-tube extending down into the can, and separable connections from 115 the tap to the tube.

4. In an air system of an ice plant, an air supply lateral, a tap therefrom where the section of the pipe is curved and having a shoulder, an air drop tube connected with the tap and a solid washer of soft metal between the tap and the pipe having one side of the washer channeled to overlap the sides of the pipe and adapted to be permanently altered in its shape by the pressure to con- 120 130

form to and seal against the side surface of the pipe.

5. In an air system for an ice plant, an air supply pipe, a tap for drawing air therefrom, a flexible connection from the tap and a terminal upon said connection having two taper fit portions of different diameters and adapted to fit air pipes of different sizes.

6. In an air system for an ice plant, an air supply pipe, a tap for drawing air therefrom, a flexible connection from said tap, a terminal upon said flexible connection, having two taper fit portions of different external diameters of terminal, an ice can, an air pipe therefor fixed against the wall of the can and having an internal diameter for connection with one diameter of the terminal and a second air pipe independent of said can, intended to supply air to the can from said terminal and having a different interior diameter for the other diameter of the terminal.

7. In an air system for an ice plant, a block of cans adapted to act as a unit, an air lateral rigidly secured to the block, taps from the lateral at intervals, flexible connections from said taps, air pipes rigidly secured to the walls of the cans and terminals between the flexible connections and the air pipes bent laterally and downwardly to free the flexible connection from the path of ice discharge.

8. In an air system for an ice plant, a block of cans adapted to act as a unit, an air lateral rigidly secured to the block, taps from the lateral at intervals, flexible connections from said taps, air pipes rigidly secured to the walls of the cans, terminals between the flexible connections and the air pipes, said terminals being bent laterally and downwardly to free the flexible connection from the path of ice discharge and being of different diameters adapted to fit either in said fixed pipes or in a removable air pipe of larger diameter.
